UNITED STATES PATENT OFFICE.

GRANVILL E. LILLY, OF GLEN MORGAN, WEST VIRGINIA, ASSIGNOR OF ONE-HALF TO
J. A. LILLY, OF GLEN MORGAN, WEST VIRGINIA.

AUTOMATIC CAR-COUPING.

1,174,878.

Specification of Letters Patent.

Patented Mar. 7, 1916.

Application filed August 19, 1915. Serial No. 46,284.

To all whom it may concern:

Be it known that I, GRANVILL E. LILLY, a citizen of the United States, residing at Glen Morgan, in the county of Raleigh and State of West Virginia, have invented certain new and useful Improvements in Automatic Car-Couplings, of which the following is a specification.

This invention relates to automatic car couplers, and particularly to couplers especially designed for use on mine cars and the like, of relatively small size.

Owing to the conditions under which mine cars are operated, it is essential that the coupling device be extremely simple and rugged in construction, and free from all complicated parts which might be likely to get out of order. With this in view, I have provided a coupler from which all detachable springs and pivoted parts have been eliminated, and in which the chance for breakage or derangement has been reduced to a minimum.

My improved coupler is of the hook and catch type and comprises a catch formed of a single piece of spring steel securely riveted to the car. Owing to this construction there are no parts which can become lost or misplaced.

In order that the invention may be readily understood, reference is had to the accompanying drawings forming a part of this specification, and in which,

Figure 1 is a perspective of one end of a wooden mine car equipped with the socket and catch member of my improved coupler; Fig. 2 is a perspective view of the end of an adjacent car having a pivoted hook member adapted to coöperate with the socket and catch member shown in Fig. 1; Fig. 3 is a longitudinal vertical section showing the parts of my improved coupler as they appear when in engagement; Fig. 4 is a plan view of the continuous draw bar which I preferably employ, showing the coupler hook connected thereto; Fig. 5 is a plan view of a metal car with my improved coupler applied thereto, showing a somewhat modified construction, and parts being in section; Fig. 6 is a vertical section showing the socket and catch member of the coupler illustrated in Fig. 5; and Fig. 7 is a fragmentary perspective view of a part of the socket member of the coupler shown in Figs. 5 and 6.

Referring to the drawings in detail, and particularly to Figs. 1 to 4 thereof, 1 designates the body of a wooden mine car of the usual or any suitable construction, and 2 indicates the floor of such car. As is usual, this floor projects beyond the body at each end, as shown in Figs. 1 and 2. In order to relieve the car body from the strains incident to hauling a train of such cars, I preferably equip each car with a continuous draw bar 3, in the nature of a flat strap of steel extending along the upper surface of the bottom of the car and projecting beyond the body at each end thereof, as shown. At one end, the draw bar 3 has pivoted thereto a hook 4, provided with a bifurcated end 5, adapted to embrace the end of the draw bar, the hook being connected to the draw bar by means of a bolt 6, extending through the draw bar and the bifurcated end of the hook. This hook is preferably smooth on its under surface and is provided with a beveled point 7, adjacent which, on the upper side, is formed a shoulder 8, which engages the catch hereinafter described. The other end of the draw bar 3 is extended downwardly over the projecting end of the floor 2, as shown in Fig. 3, and is preferably widened to form a smooth, flaring, inclined surface 9. This surface forms the bottom wall of the socket member. The draw bar 3 is formed with an off-set or shoulder 10, adjacent the inner end of the portion 9 thereof, and the object of this off-set is to act as a buffer to receive the impact of the end of the hook 4 when coupling.

The catch which coöperates with the hook 4 is designated in its entirety by the numeral 11, and consists simply of a piece of steel thinned at its middle so as to be somewhat resilient, and secured at its inner end 13 to the draw bar 3, by means of screws or bolts 14. This hook is, in reality, nothing more than a leaf spring secured at one end to the draw bar and having its outer end flaring upwardly, as clearly shown in Fig. 3. The catch is formed by a shoulder 12 cut in the lower face of such spring member. It will thus be seen that the free end of the catch 105 member 11 and the extended end 9 of the draw bar form, between themselves, a flaring mouth or socket having converging top and bottom walls, such socket being adapted to receive the swinging hook 4.

In order to release the catch from the hook, I preferably provide the following mechanism. A tail-piece 15 is riveted or otherwise secured to the catch 11 and extends upwardly substantially parallel with but somewhat spaced from the end wall of the body 1. A lug or cam 16 is carried by a transverse shaft 17 and arranged to engage the tail-piece 15. This shaft 17 is journaled in suitable brackets 18, secured to the car body, and is provided at its ends with cranks or handles 19. It is evident that when the shaft 17 is rotated in a clockwise direction, as viewed in Fig. 3, the lug 16 will bear against the tail-piece 15 and thus lift the catch 11 sufficiently to cause the shoulder 12 thereof to disengage the hook 4. The latch and associated parts are preferably inclosed in a suitable housing. This is illustrated in Figs. 1 and 3 and is preferably formed of sheet metal. It has a top wall 20 and side walls 22, the side walls being formed with valves 21 and 23, adapted to be secured to the car body. The front edge of the wall 20 is preferably rounded, as indicated at 20^a in Fig. 3, so as to substantially cover and conceal the latch 11. The side members 22 should also flare slightly outward. It will be seen that these flaring side members, together with the latch 11 and inclined end 9 of the draw bar, form a socket having a relatively large mouth, but tapering back to a comparatively small throat in which the shoulder of the catch is located. It is obvious, therefore, that when the ends of two cars equipped respectively as shown in Figs. 1 and 2, are brought together, the hook 4 will enter the mouth of the socket member and will ride along one or more of the inclined flaring walls thereof and be thereby guided into engagement with the catch. Owing to this construction, it is obvious that even though the hook 4 should be somewhat too low, it will nevertheless ride up on the inclined surface 9, while if its end is too high, it will ride down the inclined surface of the catch 11. Also, if not properly centered, the side walls 22 of the housing will guide the hook into coupling position. It will, of course, be understood that the object of the pivot 6 is to permit the hook to swing when the cars are taking a curve.

In Figs. 5 to 7, inclusive, I have shown how the same principles of construction may be applied to steel cars such as are now in common use. With this class of cars, the continuous draw bar is not necessary and the hook 4 is pivoted directly to the extended end 2' of the floor. In place of the draw bar, with its inclined flaring end 9, I employ

a member 24 having an inclined flaring end 29, similar in form and function to the end 9 of the draw bar. This member 24 is also provided with a shoulder 30, corresponding in function with the shoulder 10 of the draw bar. The inner end of the member 24 is bifurcated so as to embrace the floor of the car, as indicated at 25, and may be secured in position by suitable rivets 26. The edge of the floor may be notched out to receive the member 24, as indicated at 2^a.

The hook 11 and associated parts are similar in construction and operation to that above described. This hook is mounted directly upon the member 24 and secured in position by means of suitable bolts or rivets 26. A suitable housing 20' is provided and is secured to the body 1' and floor 2' in any desired manner. The same releasing means are employed as illustrated in Figs. 1 to 3.

It will thus be seen that by the use of a catch member in the end of a leaf spring, I have eliminated all troublesome parts and have provided an exceptionally rugged and practical coupler for the purpose indicated, and it is thought that the many advantages thereof will be fully appreciated without further discussion.

What I claim is:

1. An automatic car coupler comprising a hook and socket, said socket having a spring catch, a drawbar having a downwardly flaring end to form an inclined wall up which said hook may ride into engagement with said catch, and said drawbar being bent upwardly adjacent the inner end of said inclined wall to form a shoulder, said shoulder serving as a buffer to receive the impact of the end of the hook, when coupling, and said spring catch being secured to the drawbar just above said shoulder.

2. An automatic car coupler comprising a hook and catch, said catch consisting of a leaf spring, a tail-piece secured to said spring, a rock shaft, and means operated by said shaft to swing said tail-piece so as to release said catch from the hook.

3. The combination with a car, of a continuous draw bar extending through the same, a coupler comprising a hook and catch, said catch consisting of a leaf spring secured directly to said draw bar and having a hook-engaging shoulder formed on the lower side thereof, and said draw bar being extended underneath said shoulder to form a guideway between itself and catch to receive said hook.

In testimony whereof I have affixed my signature.

GRANVILL E. LILLY.
